UNITED STATES PATENT OFFICE

2,220,013

METHOD OF OBTAINING NAPHTHENIC ACIDS

Johannes H. Bruun, Swarthmore, Pa., assignor to
Sun Oil Company, Philadelphia, Pa., a corporation of New Jersey

No Drawing. Application February 5, 1936,
Serial No. 62,436

10 Claims. (Cl. 260—514)

The present invention relates to a process for obtaining practically pure naphthenic acids from impure naphthenic soap solutions or from lubricating oil still bottoms containing sodium or other alkali naphthenates.

In the distillation of lubricating oils from paraffin base, mixed base, or asphaltic base crudes, where an addition of sodium hydroxide or other alkali metal base is made before or during the distillation, sodium, or other alkali metal soaps of petroleum naphthenic or fatty acids are formed. Similarly to most inorganic sodium salts, these soaps cannot be distilled by ordinary methods and consequently may remain in the still bottoms. This is true regardless of what type of crude the stock being distilled may be derived from, but in the case of paraffin or some predominately paraffin mixed base crudes the percentage of soaps will be materially less. The largest amount of soaps will be formed in the distillation of true asphaltic crudes, a lesser percentage in mixed base, and a still smaller percentage in paraffin base crudes. In fact, the recovery of soaps from paraffinic crude residues may not be important from the standpoint of soap recovery but important only as a means of freeing the bottoms of soaps to render them non-emulsifiable.

If the crude is a "coastal type" asphaltic base, and is treated as disclosed in Pew Patent No. 1,761,153, issued June 3, 1930, the bottoms remaining after distillation will contain asphalt, some lubricating oil of extremely high viscosity, and sodium soaps of the acid series of the following general formulae:

$C_nH_{2n-10}O_2$ (3) and probably some the series

For these formulas the number of carbon atoms, n , may vary from 16 to 40.

Thus there would be present the soaps of the several acids of each series, the soaps probably being as follows:

$C_{37}H_{65} COONa$ (3) and possibly others

which have not yet been isolated. The total amount of such acids present in this type of crude, before distillation, may be about .7%.

A mixed base crude would probably contain some of the acids mentioned above and in addition would probably contain some acids of the series whose general formula is $C_nH_{2n-2}O_2$. The total acid content of this type crude would be somewhat less than that of a "coastal type" asphaltic base crude.

A paraffin base crude, such as Pennsylvania crude, would have a very low acid content, probably about .03% and would consist predominantly of acids of the series whose general formulae is $C_nH_{2n}O_2$ and $C_nH_{2n-2}O_2$.

The still bottoms, containing the sodium or other alkali metal soaps of the above mentioned petroleum naphthenic acids, may be treated in accordance with the present invention to remove these soaps, in case a paraffin base crude is being distilled, or to recover the valuable petroleum naphthenic acids corresponding thereto, in case a mixed base or asphaltic base crude is being distilled.

I have discovered that these petroleum naphthenic acids are soluble in liquefied normally gaseous hydrocarbons, or mixtures of the same; such as propane or commercial mixtures of propane with other normally gaseous hydrocarbons, such as propylene, butane, iso-butane, and the like, while the sodium or other alkali metal soaps of these acids are insoluble in such liquefied normally gaseous hydrocarbons. Certain other constituents of the still bottoms are soluble in propane at normal or slightly elevated temperatures, principally any heavy lubricating oil which was not distilled over during the distillation. Such oil is a very heavy and viscous one, having a high flash point and is quite valuable. It has heretofore been impossible to recover such heavy oil free from the alkali metal soaps of the petroleum naphthenic acids contained in the still bottoms.

When a "coastal type" asphaltic base crude is being distilled, the still bottoms will consist of approximately 70 parts of heavy lubricating oil of the following characteristics:

Gravity	17.3
Flash	F 600°
Fire	F 695°
Say. Vis. at 210° F	seconds 575
Say. Vis. at 130° F	do 3445

about 12 parts of naphthenic acids of the type enumerated above and about 18 parts of asphalt

having a melting point of about 300-315° F. and containing petroleum resins and other asphaltic impurities.

It is therefore an object of this invention to provide a method for obtaining practically pure petroleum naphthenic or fatty acids or their soaps from the still bottoms remaining after a crude petroleum has been distilled in the presence of an alkali.

10 A further object is to provide a method for producing a cutting oil from such still bottoms.

Still another object is to provide a method for producing an emulsifiable road asphalt from such still bottoms.

15 Other and further objects will be apparent as this description progresses.

When it is desired to recover these petroleum naphthenic or fatty acids from the asphaltic still bottoms containing the sodium or other 20 alkali metal soaps of the petroleum naphthenic or fatty acids, in admixture with heavy lubricating oil and asphaltic impurities, the still bottoms may be first acidified by mixing a mineral acid, such as sulphuric acids, with the still bottoms in

25 an amount sufficient to convert all or the major portion of the soaps into the corresponding naphthenic or fatty acids. Preferably, the amount of mineral acid is such that it is not quite sufficient to convert all the soaps into the 30 corresponding acids, since an excess of mineral acid would have a deleterious effect on the succeeding equipment.

When the still bottoms have been acidified to the desired extent, they are then mixed with 35 propane or some other liquefied normally gaseous hydrocarbons, such as propylene, butane, isobutane, and the like, or mixtures of the same. Preferably, about 5 to 10 volumes of propane to 1 volume of acidified still bottoms are mixed together under sufficient pressure to maintain the propane in liquid form and preferably with heating to about 125-130° F. The heavy lubricating oil, and also the petroleum naphthenic or fatty acids, contained in the acidified still bottoms are 40 readily dissolved by the propane under these conditions and if the mixture is allowed to stand, the propane with the lubricating oil and the petroleum naphthenic or fatty acids dissolved therein will readily separate from the asphalt. The solution of lubricating oil and petroleum naphthenic or fatty acids in propane is then withdrawn from the asphaltic residuum.

Since these petroleum naphthenic or fatty acids are frequently used in the form of their corresponding soaps in admixture with lubricating oils as a cutting oil, the propane may be distilled off from the solution of lubricating oil, naphthenic or fatty acids and propane, and the solution of naphthenic or fatty acids and oil thus obtained 55 may be saponified in any known manner, as by the addition of an alkali metal base such as NaOH, to convert the naphthenic or fatty acids contained in the lubricating oil into their corresponding alkali metal soaps. Additional lubricating oil may then be added to this mixture of soaps and oil to form a cutting oil compound, or the mixture of soaps and oil itself may be used as a cutting oil. However, as pointed out above, the heavy oil recovered from the still bottoms is quite 60 valuable and is a type which heretofore has not been recovered. It may therefore be desirable to recover this oil free of the petroleum naphthenic or fatty acids or their soaps and mix a cheaper grade of oil with the soaps of the petroleum naphthenic or fatty acids to form a cutting oil.

If it is desired to recover this heavy lubricating oil free of the petroleum naphthenic or fatty acids or their soaps, the mixture of soaps and oil instead of being mixed with additional lubricating oil to form a cutting oil may be mixed with liquefied propane preferably at a temperature of 125-130° F. and in a ratio of 5 to 10 volumes of liquefied propane to one volume of petroleum naphthenic or fatty acid soaps and oil. Under these conditions the heavy lubricating oil is readily dissolved by the propane while the petroleum naphthenic or fatty acid soaps are not. The solution of lubricating oil in propane may readily be separated from the soaps, as by allowing the mixture to stand to permit the soaps to settle out 15 and then drawing off the solution of propane and oil separately from the soaps.

A slight modification of the process described above, for recovering the lubricating oil free of the petroleum naphthenic or fatty acids or their soaps, is to take the solution of lubricating oil and petroleum naphthenic or fatty acids in propane obtained from the still bottoms by the propane extraction first described above and saponifying the petroleum naphthenic or fatty acids in propane in an amount sufficient to convert the petroleum naphthenic or fatty acids into their corresponding soaps. Since the petroleum naphthenic or fatty acid soaps are not soluble in propane, they will be precipitated and the solution of lubricating oil and propane may be separated from the soaps in any desired manner as permitting the mixture to stand and drawing off the solution of lubricating oil and propane after the soaps have settled out. The propane may then be separated from the heavy lubricating oil by distillation, thus yielding a heavy lubricating oil having the characteristics described above. While the alkali metal soaps of the petroleum naphthenic or fatty acids thus obtained will be of the type heretofore described and may be used for any desired purpose as by mixing them with lubricating oil to form a cutting oil, or other soluble or emulsifiable oil. The soaps if again acidified have a saponification value of 80-160 mg. of KOH per gram.

At times it may be desirable to recover an asphalt containing a small percentage of soaps of the petroleum naphthenic or fatty acid soaps, as when it is desired to produce an emulsifiable road asphalt. In such case the still bottoms may be acidified by mixing with them such an amount of mineral acid that only a portion of the soaps contained therein will be converted into the corresponding naphthenic petroleum or fatty acids and a sufficient amount of the petroleum naphthenic or fatty acids will remain in the form of their alkali metal soaps so that when the acidified still bottoms are mixed with propane and the heavy lubricating oil and petroleum naphthenic or fatty acids thus extracted from the asphaltic constituents, as described heretofore, the asphalt so recovered will contain the desired percentage of soaps for making an emulsifiable road asphalt. The amount of soaps left in the asphalt will, of course, depend on the specifications for the road emulsion and on whether the asphalt so recovered is to be used alone or mixed with other oils and/or asphalts.

While I have described my process in connection with obtaining naphthenic acids from the still bottoms remaining after a lubricating oil has been distilled in the presence of an alkali metal base, it is apparent that my process may be used for purifying naphthenic acids which

have been recovered from the still bottoms by some other method, for instance by the "pressure settling" method described in Angstadt Patent No. 1,931,880. In fact, it should be understood that the production of such still bottoms, being incidental to the distillation of lubricating oils in the presence of an alkali metal base, is merely one, and perhaps the simplest, way of obtaining the starting material to which I apply my process. The starting material may be obtained in any other way. For example, in the process set forth in my hereinafter mentioned application, of which this application is a division, suitable starting material is obtained by mixing such still bottoms with propane to dissolve the heavy lubricating oil that is contained in the still bottoms, and separating the solution of propane and oil from the mixture of asphalt and soaps, which affords a suitable starting material. As described in the specification of said application, and in this specification, the mixture is then acidified to break down the soaps to form naphthenic and fatty acids, liquid propane or another normally gaseous hydrocarbon is added to dissolve the acids, and the solution is separated from the asphalt. The purified naphthenic acids, or the soaps of these acids when again acidified, have a saponification value of 80 to 160 mg. of KOH per gram and are most suitable for use in the form of their corresponding soaps in preparing soluble oils and oil emulsions of all kinds.

While I have particularly mentioned propane in the above description of my process, it is to be understood that other liquefied normally gaseous hydrocarbons such as ethane, ethylene, propylene, butane, iso-butane, and the like or mixtures of the same, with or without propane, may be used instead of propane, and where the term "liquefied normally gaseous hydrocarbon" is used in the appended claims it is to be understood as including such compounds and mixtures.

This application is a continuation-in-part of my copending application Serial No. 16,607, filed April 16, 1935.

What I claim and desire to protect by Letters Patent is as follows:

1. The method of separating the soaps of petroleum naphthenic and fatty acids from a mixture of the same with asphalt, such as is produced as still bottoms from the distillation of petroleum in the presence of an alkali metal base, which comprises acidifying said mixture to break down said metal soaps of said petroleum naphthenic and fatty acids to form the corresponding petroleum naphthenic and fatty acids, mixing said acidified mixture with a liquefied normally gaseous hydrocarbon to dissolve said petroleum naphthenic and fatty acids and separating said liquefied normally gaseous hydrocarbon with said petroleum naphthenic and fatty acids dissolved therein from said asphalt.

2. The method of making a cutting oil from a mixture of the soaps of petroleum naphthenic and fatty acids with heavy lubricating oil and asphalt, such as is produced as still bottoms remaining after the distillation of a crude petroleum in the presence of an alkali metal base, which comprises acidifying said mixture to convert the said soaps into their corresponding petroleum naphthenic and fatty acids, mixing the thus acidified mixture with a liquefied normally gaseous hydrocarbon to dissolve said heavy lubricating oil and said petroleum naphthenic and fatty acid soaps.

3. The method of making a cutting oil from a mixture of the metal soaps of petroleum naphthenic and fatty acids with heavy lubricating oil and asphalt, such as is contained in asphaltic still bottoms remaining after the distillation of a crude petroleum in the presence of an alkali metal base, which comprises acidifying said mixture to convert the said soaps into their corresponding petroleum naphthenic and fatty acids, 5 mixing the thus acidified mixture with a liquefied normally gaseous hydrocarbon to dissolve said heavy lubricating oil and said petroleum naphthenic and fatty acids, separating the said liquefied normally gaseous hydrocarbon with said heavy lubricating oil and said petroleum naphthenic and fatty acids dissolved therein from the asphalt, removing said liquefied normally gaseous hydrocarbon from said heavy lubricating oil and said petroleum naphthenic and fatty acids, 10 saponifying said solution of heavy lubricating oil and said petroleum naphthenic and fatty acids to convert said petroleum naphthenic and fatty acids into their corresponding soaps.

4. The method of recovering petroleum naphthenic and fatty acid soaps from a mixture of the same with heavy lubricating oil and asphalt, such as is produced as still bottoms remaining after the distillation of a crude petroleum in the presence of an alkali metal base, which comprises acidifying said mixture to convert the said soaps into their corresponding petroleum naphthenic and fatty acids, 15 mixing the thus acidified mixture with a liquefied normally gaseous hydrocarbon to dissolve said heavy lubricating oil and said petroleum naphthenic and fatty acids dissolved therein from the asphalt, removing said liquefied normally gaseous hydrocarbon from said heavy lubricating oil and said petroleum naphthenic and fatty acids, 20 saponifying said solution of heavy lubricating oil and said petroleum naphthenic and fatty acids to convert said petroleum naphthenic and fatty acids into their corresponding soaps and adding lubricating oil to the mixture 25 of heavy lubricating oil and soaps to form a cutting oil.

5. The method of recovering petroleum naphthenic and fatty acid soaps from a mixture of the same with heavy lubricating oil and asphalt, such as is produced as still bottoms remaining after the distillation of a crude petroleum in the presence of an alkali metal base, which comprises acidifying said mixture to convert the said soaps into their corresponding petroleum naphthenic and fatty acids, 30 mixing the thus acidified mixture with a liquefied normally gaseous hydrocarbon to dissolve said heavy lubricating oil and said petroleum naphthenic and fatty acids dissolved therein from the asphalt, removing said liquefied normally gaseous hydrocarbon from said heavy lubricating oil and said petroleum naphthenic and fatty acids, 35 saponifying said solution of heavy lubricating oil and said petroleum naphthenic and fatty acids to convert said petroleum naphthenic and fatty acids into their corresponding soaps and adding lubricating oil to the mixture 40 of heavy lubricating oil and soaps to form a cutting oil.

6. The method of recovering petroleum naphthenic and fatty acid soaps from a mixture of the same with heavy lubricating oil and asphalt, such as is produced as still bottoms remaining after the distillation of a crude petroleum in the presence of an alkali metal base, which comprises acidifying said mixture to convert the said soaps into their corresponding petroleum naphthenic and fatty acids, 45 mixing the thus acidified mixture with a liquefied normally gaseous hydrocarbon to dissolve said heavy lubricating oil and said petroleum naphthenic and fatty acids dissolved therein from the asphalt, removing said liquefied normally gaseous hydrocarbon from said heavy lubricating oil and said petroleum naphthenic and fatty acids, 50 saponifying said solution of heavy lubricating oil and said petroleum naphthenic and fatty acids to convert said petroleum naphthenic and fatty acids into their corresponding soaps, mixing the mixture of heavy lubricating oil and soaps then formed with a liquefied normally gaseous hydrocarbon to dissolve said heavy lubricating oil and precipitate said soaps, and separating said liquefied normally gaseous hydrocarbons with said heavy lubricating oil dissolved therein from said petroleum naphthenic and fatty acid soaps.

7. The method of recovering petroleum naphthenic and fatty acid soaps from a mixture of the same with heavy lubricating oil and asphalt, such as is produced as still bottoms remaining after the distillation of a crude petroleum in the presence of an alkali metal base, which comprises acidifying said mixture to convert the said soaps into their corresponding petroleum naphthenic and fatty acids, 55 mixing the thus acidified mixture with a liquefied normally gaseous hydrocarbon to dissolve said heavy lubricating oil and said petroleum naphthenic and fatty acids dissolved therein from the asphalt, removing said liquefied normally gaseous hydrocarbon from said heavy lubricating oil and said petroleum naphthenic and fatty acids, 60 saponifying said solution of heavy lubricating oil and said petroleum naphthenic and fatty acids to convert said petroleum naphthenic and fatty acids into their corresponding soaps, mixing the mixture of heavy lubricating oil and soaps then formed with a liquefied normally gaseous hydrocarbon to dissolve said heavy lubricating oil and precipitate said soaps, and separating said liquefied normally gaseous hydrocarbons with said heavy lubricating oil dissolved therein from said petroleum naphthenic and fatty acid soaps.

and fatty acids, mixing the thus acidified mixture with a liquefied normally gaseous hydrocarbon to dissolve said heavy lubricating oil and said petroleum naphthenic and fatty acids, separating said liquefied normally gaseous hydrocarbon with said heavy lubricating oil and said petroleum naphthenic and fatty acids dissolved therein from the asphalt, saponifying said solution of heavy lubricating oil and petroleum naphthenic and fatty acids in said liquefied normally gaseous hydrocarbons to convert said petroleum naphthenic and fatty acids into their corresponding soaps and separating said liquefied normally gaseous hydrocarbon with said heavy lubricating oil dissolved therein from the thus precipitated petroleum naphthenic and fatty acid soaps.

6. The method of making an asphaltic road emulsion and a cutting oil from a mixture of petroleum naphthenic and fatty acid soaps with heavy lubricating oil and asphalt such as is contained in the asphaltic still bottoms remaining after distilling a crude petroleum in the presence of an alkali metal base, which comprises adding a mineral acid to said mixture in an amount sufficient to convert a part of said soaps into their corresponding petroleum naphthenic and fatty acids, mixing a liquefied normally gaseous hydrocarbon with said partly acidified mixture to dissolve said heavy lubricating oil and said petroleum naphthenic and fatty acids, separating said liquefied normally gaseous hydrocarbons with said heavy lubricating oil and said petroleum naphthenic and fatty acids dissolved therein from a residue of asphalt and petroleum naphthenic and fatty acid soaps suitable for a road emulsion, removing said liquefied normally gaseous hydrocarbons from said heavy lubricating oil and said petroleum naphthenic and fatty acids, and saponifying said solution of heavy lubricating oil and petroleum naphthenic and fatty acids to convert said acids into their corresponding soaps and thus form a cutting oil.

7. The method of recovering the soaps of petroleum naphthenic and fatty acids from a crude starting material which contains such soaps in admixture with heavy lubricating oil, asphalt, petroleum resins, and other asphaltic impurities, which comprises acidifying said starting material to convert said soaps into their corresponding petroleum naphthenic and fatty acids, mixing the thus acidified starting material with a liquefied normally gaseous hydrocarbon to dissolve said heavy lubricating oil and said petroleum naphthenic and fatty acids, separating said liquefied normally gaseous hydrocarbon with said heavy lubricating oil and said petroleum naphthenic and fatty acids dissolved therein from the as-

phalt, removing said liquefied normally gaseous hydrocarbon from said heavy lubricating oil and said petroleum naphthenic and fatty acids, saponifying said solution of heavy lubricating oil and said petroleum naphthenic and fatty acids to convert said petroleum naphthenic and fatty acids into their corresponding soaps, mixing the mixture of heavy lubricating oil and soaps then formed with a liquefied normally gaseous hydrocarbon to dissolve said heavy lubricating oil and precipitate said soaps, and separating said liquefied normally gaseous hydrocarbons with said heavy lubricating oil dissolved therein from said petroleum naphthenic and fatty acid soaps.

8. The method of recovering the soaps of petroleum naphthenic and fatty acids from a crude starting material which contains such soaps in admixture with heavy lubricating oil, asphalt, petroleum resins, and other asphaltic impurities, which comprises acidifying said starting material to convert said soaps into their corresponding petroleum naphthenic and fatty acids, mixing the thus acidified starting material with a liquefied normally gaseous hydrocarbon to dissolve said heavy lubricating oil and said petroleum naphthenic and fatty acids, separating said liquefied normally gaseous hydrocarbon with said heavy lubricating oil and said petroleum naphthenic and fatty acids dissolved therein from the asphalt, saponifying said solution of heavy lubricating oil and petroleum naphthenic and fatty acids in said liquefied normally gaseous hydrocarbons to convert said petroleum naphthenic and fatty acids into their corresponding soaps and separating said liquefied normally gaseous hydrocarbon with said heavy lubricating oil dissolved therein from the thus precipitated petroleum naphthenic and fatty acid soaps.

9. A method of purifying crude naphthenic acids derived from petroleum, shale oil, coal tar and like fractions which comprises commingling said acids with a liquefied normally gaseous hydrocarbon solvent to dissolve the naphthenic acids but not the impurities present therein and separating the solution of naphthenic acids dissolved in said solvent from the undissolved impurities.

10. A method of purifying naphthenic acids containing asphalt-like substances which comprises commingling said acids with a liquefied normally gaseous hydrocarbon to dissolve the naphthenic acids and to precipitate said asphalt-like substance and separating the solution of naphthenic acids dissolved in the liquefied normally gaseous hydrocarbon from the precipitated asphalt-like substances.

JOHANNES H. BRUUN.
